UNITED STATES PATENT OFFICE.

ANSELME BERNIER, OF BIDDEFORD, MAINE.

THREADING DEVICE FOR SHUTTLES.

Application filed March 23, 1926. Serial No. 96,813.

This invention relates to improvements in threading devices for loom shuttles, and the primary object of the present invention is to provide a novel form of threading device which will effectively prevent the passage of bunches or knots at the entry thereof, and which will place the thread under tension so as to make the cloth even in texture, and prevent bunches or knots appearing in the cloth.

A more specific object of the invention is to provide an automatic threading device for automatic filling replenishing loom shuttles with simple and effective means for preventing the passage of bunches or knots at the entry of the threading device, and for placing the thread under tension so as to make the cloth even in texture, and prevent bunches or knots appearing in it.

A further object of the invention is to provide a bunch or knot detecting device and thread guiding and tensioning means which can be readily applied to usual forms of shuttles without material changes in the form of the threading device or modification of the shuttles.

Other objects will appear as the nature of the invention is better understood, and the same consists in the novel form, combination and arrangement of parts hereinafter more fully described, shown in the accompanying drawing and claimed.

In the drawing, wherein like reference characters indicate corresponding parts throughout the several views,

Figure 1 is a plan view of the front end of a shuttle adapted for use in an automatic filling replenishing loom and having a threading device equipped with a bunch or knot detecting means and thread tensioning means constructed in accordance with the present invention;

Figure 2 is an end elevation looking at the inner end of the threading device shown in Figure 1;

Figure 3 is a detail view, partly in longitudinal section, of the front end of the shuttle and threading device illustrated in Figure 1;

Figure 4 is a fragmentary horizontal sectional view of the threading device taken substantially upon line 4-4 of Figure 3;

Figure 5 is a bottom plan view of the threading device; and

Figure 6 is an end elevational view of the

threading device looking at the outer end thereof.

The invention is disclosed in the accompanying drawing as applied to a usual form of shuttle for automatic filling replenishing looms comprising a body portion 5 having a chamber 6 for a filling carrier 7 and a channel 8 leading from said chamber in the direction of the axis of the shuttle, the shuttle having a side eye 9 and threading slot 10 leading from said eye to the channel 8.

A threading device 11, which is secured within the channel 8, is provided with a thread passage leading to the eye and with means for directing the thread or filling running from the filling carrier into said thread passage during the flight of the shuttle across the loom. The threading device may be constructed in any suitable manner to embody the improved bunch or knot detecting and thread tensioning means therein. In the preferred embodiment illustrated in the accompanying drawing, the threading device 11 comprises a solid block having a thread passage 12 in the form of a cylindrical aperture or bore extending longitudinally therethrough and located substantially in the longitudinal axis of the shuttle. A second cylindrical aperture or bore 13 is located directly above the bore 12, said apertures or bores being located in such proximity that a portion of the wall between them is cut away to form a threading slot 14.

The outer or forward end of the threading device 11 presents an inturned beak 15 having a rearwardly extending horn 16 which projects across the vertical axial plane of the shuttle and serves to prevent the filling from escaping from the thread aperture when introduced therein. The front wall of the beak 15 is so located as to form the rear wall of the threading slot 10 leading to the eye 9 of the shuttle, and may be provided with a flanged portion 17 which enters a complementary notch in the body of the shuttle for aiding in securing the threading device firmly in place.

The threading device is provided at its front end with a shield 18 which overhangs the beak 15 and horn 16 and is supported therefrom a sufficient distance to permit the introduction of the thread, the beak and shield thus positioned providing means for guiding the thread into the threading slot during the flight of the shuttle across the

loom and serving to retain the thread within the thread passage 12 and eye 9 after it has been introduced.

In accordance with the present invention 5 a transverse plate or wall 19 is fixed at the inner ends of the passages 12 and 13 and provided with a vertical elongated and narrow slot 20 which opens through the upper edge of the plate 19 and which is 10 located in a longitudinal plane co-incident with the longitudinal axes of the passages 12 and 13 for reception of the thread or filling. The slot 20 is of such width as to 15 permit the passage of the thread and at the same time cause the latter to frictionally engage the sides of the slot, to aid in placing the thread or filling under tension. It is 20 obvious that the slot 20, being of such character, will effectively prevent the passages 25 of bunches or knots into the thread passage 12 so that the cloth may be made even in texture or without bunches or knots appearing in the same. In the preferred embodiment shown, the plate 13 constitutes a wall 30 formed rigidly with the inner end of the threading device.

A vertical elongated and narrow loop 21 is attached to the forward or outer end 35 of the threading device so that the lower portion of the same depends into the forward or outer end of the thread passage 12 centrally between the sides of the latter as clearly shown in Figure 6, and it will thus be seen that when the thread is led between 40 the arms of the loop 21 from the slot 20, such thread will be effectively centered in the thread passage. The space between the arms of the loop 21 is similar to the width of the slot 20 so that the loop 21 frictionally 45 engages the thread as it passes from the forward or outer end of the thread passage 12 to the eye 9 of the shuttle. Thus, the plate 19 and loop 21 cooperate to place the thread under tension for further insuring an 50 even texture of the cloth. As shown, the loop 21 is formed from a single strip of resilient metal centrally return bent and having its free upper ends directed apart and soldered or otherwise secured to the sides 55 of the upper longitudinal bore or passage 13 as generally indicated at 22. In this way the loop 21 is formed so as to be open at its upper end and provided with a flared entrance for permitting the passage of the 60 thread from the bore 13 through the slot 14 into the thread passage 12 with said thread maintained centrally of the passage 12 between the sides of the lower portion of the loop.

65 From the foregoing description it will be seen that the slotted plate 13 and loop 21 form a simple and inexpensive means for effectively preventing the passage of bunches or knots from the shuttle and before reaching the eye 9 of the latter, while at

the same time cooperating for effectively placing the thread under tension and in a straight condition in the thread passage 12.

While the preferred form of the invention 70 contemplates the modification of a threading device involving the provision of the latter with the slotted plate 13 and loop 21, it is nevertheless to be understood that the invention broadly contemplates the provision of these elements 19 and 21 in the 75 relation shown between the filling carrier and the shuttle eye apart from a threading device, if desired.

It will be understood that various modifications in form, construction and arrangement of parts may be made within the spirit 80 and scope of the following claims.

What I claim as new is:—

1. A loom shuttle having a chamber for a filling carrier, a thread delivery eye, a channel extending longitudinally of said shuttle leading to said eye, and means located in said channel for placing the thread under tension and preventing the passage of bunches and knots to said eye, said last named means embodying a transverse plate having a vertical narrow thread guiding slot of uniform width and opening through the upper edge of the plate, said plate being mounted in the inner end portion of said channel, and a narrow vertically elongated loop open at its upper end and rigidly mounted in the outer end portion of said channel for guiding and frictional engagement with the thread in its passage to the 100 eye.

2. A loom shuttle having a chamber for a filling carrier, a thread delivery eye, a channel extending longitudinally of said channel leading to said eye, a threading 105 device in said channel having a thread passage extending longitudinally of the shuttle, and thread tensioning and knot detecting means in said thread passage, said last named means comprising a plate rigid with the inner end of the threading device and having a vertical narrow slot of uniform width opening through the upper edge thereof, and a narrow vertically elongated loop rigidly mounted on the outer end of the threading device and centrally depending into the outer end of said thread passage.

3. A loom shuttle having a chamber for a filling carrier, a thread delivery eye, a channel extending longitudinally of said channel leading to said eye, a threading device in said channel having a thread passage extending longitudinally of the shuttle, and thread tensioning and knot detecting 120 means in said thread passage, said last named means comprising a plate rigid with the inner end of the threading device and having a vertical narrow slot of uniform width opening through the upper edge thereof.

of, and a narrow vertically elongated loop rigidly mounted on the outer end of the threading device and centrally depending into the outer end of said thread passage, said loop having an open upper end forming a flared thread entrance.

4. A loom shuttle having a chamber for a filling carrier, a thread delivery eye, a channel extending longitudinally of said shuttle, a transverse threading slot leading from said channel to said eye, a threading device in said channel comprising a block having a longitudinally extending cylindrical bore forming a thread passage, a longitudinally extending bore above said thread passage, the wall between said bores being

slotted to provide a guideway for introducing the thread into said thread passage, a beak, a shield overlying said beak, a vertical elongated narrow loop comprising a strip of material with upper free ends expanded and secured to the sides of the second named bore, whereby the loop is suspended to depend through the guideway centrally of the outer end of the thread passage, and a plate 25 rigid with the inner end of the threading device and having a vertical narrow slot opening through the upper edge thereof in longitudinal alignment with the axes of the bores.

In testimony whereof I affix my signature.
ANSELME BERNIER.
